CONTINUOUS FLOW APPARATUS FOR TESTING PULP FREENESS

Charles Oland Sisler, Sault Ste. Marie,
Ontario, Canada

Application February 5, 1944, Serial No. 521,247

6 Claims. (Cl. 73—63)

This invention relates to apparatus for testing and recording pulp "freeness" or "slowness." The property of water drainage through a pulp slush suspended on a woven wire or perforated plate is used in the paper or pulp board manufacturing process. Water drainage rate is also used as a means of evaluation of pulp quality or suitability for various paper making requirements when a standard weight of pulp in suspension is drained of its contained water by means of a perforated plate or woven wire under standardized conditions. The resultant volume of, or time required to reach a certain specified volume of drainage under fully standardized temperature, consistency and other conditions, is a measure of the respective freeness or sedimentation time for a given pulp.

At the present time this freeness or sedimentation test data, hereinafter called "freeness," is generally secured by individual separate tests on samples removed from time to time from the pulp system. This invention relates to a machine into which is fed a continuous flow of the slush pulp to be tested and which delivers the freeness test data continuously on a chart or by other means.

The object of this invention is to provide a simple and accurate means for obtaining continuous immediate freeness data on pulp from a pulp production or preparation system, thereby avoiding delay in securing this quality information.

With the above objects in view the invention consists of a horizontal or sloped belt of woven wire of suitable mesh and size, driven at a predetermined selected constant speed, upon which a constant volume per second of the pulp stock to be tested is uniformly fed and distributed.

The pulp sample is supplied to the machine from a commercial pulp regulator at a consistency common to these types of regulators. Means are provided for either heating or cooling the water and the pulp stock within the mixer. A constant volume of the pulp sample is mechanically mixed with a constant volume of fresh water and the mixture controlled to a constant temperature, so that a constant volume per second of constant temperature and consistency is permitted to flow through suitable ducts to a suitable slot or slice opening at the head end of the wire belt.

The continuous drainage of water from the film of pulp carried by the moving wire belt is all or part collected by a tray located beneath the wire belt and thence conducted to a suitable

volumetric measuring device, which continuously reports or records the flow per unit of time in terms of pulp freeness. Means are provided for the continuous removal of the pulp film at the end of the wire belt or close to the point of its change of direction to return.

The invention is hereinafter more particularly described and is illustrated by way of example, in the accompanying drawing, in which

Figure 1 is a diagrammatic side elevation of the apparatus, and

Figure 2 a diagrammatic side elevation of an alternative flow measuring device and recorder.

An inlet pipe 1 conducts pulp slush stock which has been previously regulated to a uniform consistency by a commercial pulp consistency regulator from the pulp system to a constant level chamber 2 fitted with a suitable overflow opening 3 adjacent the top thereof, and an orifice 4 of suitable design in the bottom thereof. A similarly designed chamber 5, larger than chamber 2 is provided in which a constant level of fresh water is maintained, with an inlet pipe 6 and an overflow pipe 7, and an orifice of suitable design 8.

The preceding apparatus provides a constant volume discharge of pulp and water from the orifices 4 and 8 respectively. The orifices 4 and 8 consist of standard thin plates circular in shape, having a central hole and set into recesses in the bottoms of the tanks 2 and 5. These holes are so designed that a constant quantity per minute of stock and water passes through under the constant head conditions provided. The water and stock are collected by receivers 9 and 10 and conducted to a mixing chamber 11, in which a mechanical agitator 12 of suitable design is driven by an electric motor 13 or other means. In the mixing chamber 11 are located a heating or cooling coil 14 which is supplied with suitable refrigerant or heating fluids depending on whether it is necessary to heat or cool the pulp mixture.

Automatically controlled means, comprising a thermometer bulb 14a connected by tube 14b to a valve 14c, are provided so that a constant temperature will be maintained on the pulp mixture passing through the mixer. Standard temperature for freeness testing purposes is 20° C. Separate cooling and heating means or elements may be used.

From the mixing chamber 11 the mixture of pulp and water at a constant volume per second, constant temperature and consistency, is conducted by pipe 15 to the constant level headbox 17. 16 is an air vent on line 15. The headbox 17 is suitably equipped with baffles 19 to control

and smooth out the flowing stock suspension. An overflow spout 18 ensures a constant level in the headbox 17. A slotted orifice or slice 19 is provided in the wall 20 of headbox 17 from which the stock suspension is uniformly discharged in a continuous ribbon the full width of the constant speed wire mesh belt 21 at a constant velocity. The width of the orifice 19 may be varied as desired by means of a vertically adjustable gate 19a. This stream of pulp suspension is picked up and carried along by the belt which is moving at a constant predetermined rate of speed away from the slice opening at a speed more or less the same velocity as the stock being discharged. Deckle or guard straps 22 of suitable material and design are arranged on each side of the wire belt to prevent side overflow of the pulp suspension. The wire belt 21 is carried by a series of supporting rolls 23 suitably placed and is guided and tightened by rolls represented by 24 and 25. Suitable means for cleaning the wire belt 21 is provided by the steam or water shower pipe 26. Roll 27, known as a couch roll, is the only driven roll in the machine, being driven by a belt, chain or gears from motor 28 or some other power source at a suitable speed.

The water drainage from the wire 21 is wholly or partially caught by a pan 29 and led from either or both sides of the machine by a pipe or pipes 30 to a measuring device such as a tank 31 where it flows over a weir 32, and the flow is recorded by a commercial type of level recorder. Such a device is indicated diagrammatically in Figure 1, in which a diaphragm 33 is shown submerged in the liquid above the weir and connected with a recording device 37 having a rotating chart 33a and stylus 33b for inscribing a record of liquid level changes in the tank 31. The level varies with the rate of flow, this flow representing the freeness of the stock passing through the machine. The recording instrument is so calibrated in conjunction with the flow measuring device that it will record stock freeness directly.

A pan 34 having a drainage pipe 35 is provided to catch and drain off the pulp and water mixture cleaned off the wire by the spray from the shower pipe 26. Stock and water conductors bearing stock rejected from the machine and passing off through the pipes at 3, 18, 30 and 35 can be piped into a common return pipe and returned to the stock system for recovery.

In Figure 2 I have illustrated an alternative recording device comprising a standard thin plate orifice 36 in the pipe 30. This is connected by piping to a commercial differential metering recorder which will continuously record the rate of flow of liquid in the line 30 either in terms of gallons or other unit of measurement per hour, or direct in terms of pulp freeness.

What I claim as my invention is:

1. Apparatus for continuous testing of pulp freeness, comprising a mesh belt moving at a constant predetermined rate of speed, a constant level chamber for the stock, means for carrying a continuous flow of sample pulp stock from a paper pulp system to said constant level chamber, means for adding liquid to the stock in predetermined volume, means for mixing the stock and liquid to provide a uniform mixture, means for carrying the stock from the constant level chamber to the mesh belt, means for collecting the liquid from the stock that passes through the mesh belt, the stock that passes through the mesh belt, means for carrying off the liquid thus collected in

a continuous flow, and means for measuring the rate of flow of such liquid in the latter means.

2. Apparatus for continuous testing of pulp freeness, comprising a pulp constant level chamber and a water constant level chamber, means for conducting sample pulp stock to be tested from a paper pulp system to the pulp constant level chamber, means for conducting water to the water constant level chamber, a mixing chamber, means for conveying a constant volume of pulp and water from said constant level chambers to the mixing chamber, means in the mixing chamber for mixing the pulp and water, a mesh belt moving at a constant rate of speed, means through which the mixture flows to said belt from the mixing chamber, means for collecting the liquid that passes through said belt, means for carrying off the liquid thus collected in a continuous flow, and means for measuring the rate of flow of the liquid thus collected in the latter means.

3. Apparatus for continuous testing of pulp freeness, comprising a pulp constant level chamber and a water constant level chamber, means for conducting sample pulp stock to be tested from a paper pulp system to the pulp constant level chamber, means for conducting water to the water constant level chamber, a mixing chamber, means for conveying a constant volume of pulp and water from said constant level chambers to the mixing chamber, means in the mixing chamber for mixing the pulp and water, means for maintaining the temperature of the mixing chamber at a substantially constant predetermined degree, a mesh belt moving at a constant rate of speed, means through which the mixture flows to said belt from the mixing chamber, means for collecting the liquid that passes through said belt, means for carrying off the liquid thus collected in a continuous flow, and means for measuring the rate of flow of the liquid thus collected in the latter means.

4. Apparatus for continuous testing of pulp freeness, comprising a pulp constant level chamber and a water constant level chamber, means for conducting sample pulp stock to be tested from a paper pulp system to the pulp constant level chamber, means for conducting water to the water constant level chamber, a mixing chamber, means for conveying a constant volume of pulp and water from said constant level chambers to the mixing chamber, means in the mixing chamber for mixing the pulp and water, a head box having baffles therein, means through which the mixture from the mixing chamber flows to the head box, a mesh belt moving at a constant rate of speed, means through which the mixture flows to said belt from the head box, means for collecting the liquid that passes through said belt, means for carrying off the liquid thus collected in a continuous flow, and means for measuring the rate of flow of the liquid thus collected in the latter means.

5. Apparatus for continuous testing of pulp freeness, comprising a pulp constant level chamber and a water constant level chamber, means for conducting sample pulp stock to be tested from a paper pulp system machine to the pulp constant level chamber, means for conducting water to the water constant level chamber, a mixing chamber, means for conveying a constant volume of pulp and water from said constant level chambers to the mixing chamber, means in the mixing chamber for mixing the pulp and water, means for maintaining the temperature of the

mixing chamber at a substantially constant predetermined degree, a head box having baffles therein, means through which the mixture from the mixing chamber flows to the head box, a mesh belt moving at a constant rate of speed, means through which the mixture flows to said belt from the head box, means for collecting the liquid that passes through said belt, means for carrying off the liquid thus collected in a continuous flow, and means for measuring the flow of the liquid thus collected in the latter means. 10

6. Apparatus for continuous testing of pulp freeness, comprising a mesh belt moving at a constant predetermined rate of speed, a constant

level chamber for the stock, means for carrying a continuous flow of sample stock from a paper pulp system to said constant level chamber, means for mixing the stock to provide a uniform mixture, means for bringing the stock to a predetermined temperature, means for carrying the stock from the constant level chamber to the mesh belt, means for collecting the liquid from the stock that passes through the mesh belt, means for carrying off the liquid thus collected in a continuous flow, and means for measuring and recording the rate of flow in the latter means in terms of freeness.

CHARLES OLAND SISLER.
